APPARATUS FOR REMOVING LIQUID FROM
COTTON LINTERSClarence B. Weiss and Charles W. Dean, Memphis,
Tenn., assignors to Buckeye Cotton Oil Company,
Memphis, Tenn., a corporation of Ohio

Application February 17, 1947, Serial No. 729,056

3 Claims. (Cl. 92—7)

1

This invention relates to improved apparatus for use in the handling or treatment of fibrous materials such as cotton linters, and is especially adapted to the continuous processing of such materials while impregnated with or suspended in a liquid.

Basically, the apparatus consists of a screw conveyor supported for rotation in a liquid pervious cylinder, the construction being such that fibers fed through the conveyor are subjected to increasing pressure as they approach the discharge end of the conveyor, being there formed into a dense plug which offers high resistance to the movement of the fibers through the conveyor, so that entrained liquid is expressed through the cylinder wall.

It is an object of the invention to provide apparatus of this general character which is capable either of delivering fibrous material to a high pressure zone, or of discharging fibrous material from a high pressure zone, in a continuous manner and without impairment of the pressure.

A further object of the invention is the provision of a screw conveyor for the feeding of fibrous slurry in which a substantially constant pressure may be maintained at the conveyor outlet to resist the discharge of material therefrom, regardless of the rate at which the material is fed to the conveyor. In the preferred form of the invention, this object is achieved by the provision adjacent the discharge end of the conveyor of means to promote the formation of a compressed plug of the discharging fibrous material, the plug forming means being yieldably supported so as to compensate for sudden variation in the plug density or in the load imposed upon the conveyor as the result of lack of uniformity of feed of material therethrough, whereby the density and quantity of discharged material is maintained substantially constant. The conveyor is preferably of the screw type, having a screw shaft of uniform diameter and a continuous flight of uniform diameter and pitch operating in a cylindrical casing, but terminating short of the end, so that fresh material is continuously fed against and into the fibrous plug as the plug moves toward and out of the discharge end of the conveyor.

A further object of the invention is to provide

10 apparatus of the character described which is capable of releasing fibrous material to the atmosphere from a system in which substantial steam pressures are maintained, the discharging material serving to block the release of pressure from the system. It is a feature of the invention that should accidental discharge of the blocking material occur, a mechanical safety device is automatically rendered operative to prevent escape of material or steam.

15 A further object of the invention is the provision of apparatus for substantially freeing fibrous material from a liquid in which it is suspended or with which it is impregnated.

15 Still a further object of the invention is the provision of improved means for concurrently feeding and washing cotton linters, and for subjecting linters to a sequence of squeezing, impregnating, and treating steps.

20 Further objects and features of the invention will be apparent from the following description taken in connection with the accompanying drawings, in which

25 Figure 1 is a longitudinal sectional view of feeding apparatus embodying the principles of the invention and particularly adapted for use in the discharge of fibrous materials from a pressure system to the atmosphere or to a system of reduced pressure;

30 Figure 2 is a longitudinal sectional view of a further form of the feeding apparatus shown in Figure 1, modified to provide for washing of the fed materials;

35 Figure 3 is a longitudinal sectional view of a part of the apparatus shown in Figure 1 whereby the load imposed on the feeding apparatus may be regulated or controlled;

40 Figure 4 is a fragmentary longitudinal section illustrating a modified form of plug forming and retaining means;

Figure 5 is an enlarged side elevation of the end portion of the conveyor shown in Figures 1 and 2; and

45 Figure 6 is a view in section of a further modification, adapted particularly to the feeding of material at atmospheric or low pressure to a system of higher pressure.

In order to facilitate an understanding of the invention, reference is made to the several embodiments illustrated in the accompanying draw-

2

In order to facilitate an understanding of the invention, reference is made to the several embodiments illustrated in the accompanying draw-

ings, and to the preferred use of such apparatus in the handling or treatment of cotton linters, specific language being employed to describe the same. It will nevertheless be understood that no limitation of the invention is thereby intended, various alterations or modifications thereof, such as would fall within the province of those skilled in the art to construct or perform, being contemplated as part of the invention.

In the purification of the cellulosic content of cotton linters and like materials, it is convenient to process the materials, and to convey the materials from one processing zone to another, in the form of a slurry or suspension in liquid. In the course of processing it is sometimes necessary to vary the concentration or liquid to lint ratio of the slurry, to convey the material between zones in which different pressures are maintained, or to substitute one liquid medium for another. It is also often necessary to wash the material at various stages of the treatment to remove spent liquor or impurities. The apparatus herein described is effective in performing these and various other functions in a simple and uniform manner while feeding the material continuously, and is thus particularly adapted to use in a continuous treatment operation. An important feature of the apparatus is its ability to function properly even though the supply of material is irregular or discontinuous.

In Figure 1 of the drawings is illustrated an apparatus particularly designed for the discharge of cotton linters or like fibrous material from a high pressure zone to a zone of lower pressure or to atmosphere. Fibrous stock in the form of slurry is withdrawn from the high pressure zone through an inlet passage 10 into the inlet end of a screw conveyor. The conveyor consists essentially of a cylindrical housing having an inlet section 12 and an outlet section 13. The inlet section 12 of the conveyor housing is sealed, for instance by welding, to the inlet passage 10, and is impervious to liquid, so that loss of pressure from the high pressure zone is prevented. The outlet section 13 of the conveyor housing is perforated, slotted, or otherwise formed to present a liquid pervious wall, whereby liquid may be expressed from the slurry as it passes therethrough. A generally cylindrical casing 15 surrounds the outlet section 13, whereby expressed liquid is collected and led off through a discharge passage 16. The employment of conventional means for maintaining back pressure in passage 16, in order to minimize loss of steam pressure through the perforations in the outlet section 13 of the conveyor housing, is usually desirable.

A screw shaft 20, suitably journaled for rotation in the conveyor housing and driven from a convenient power source, not shown, is provided with one or more continuous screw threads or helical conveyor flights 22. To simplify illustration, only one flight is shown, although it is found that the pressure distribution on the shaft is improved by the use of at least two coextensive flights to balance the thrust. The diameter of the flight is preferably only slightly less than the internal diameter of the housing in which it rotates, the screw having a working fit in the housing. The diameters of the shaft and housing are uniform; proper operation does not depend on the use of a tapering feed passage, and is therefore independent of irregularity in the supply of material.

In this embodiment of the invention, the conveyor flight extends across the inlet passage and

terminates short of the discharge end of the outlet section 13 of the conveyor housing, it being observed that the annulus 24, on which the cylindrical perforated shell 13 and the casing 15 are mounted constitutes an extension of the housing. The purpose of terminating the conveyor flight short of the end of the housing is to permit the formation rearwardly of the conveyor flight of a plug of compressed fiber which is gradually fed out of the conveyor housing by the pressure exerted by the conveyor screw against successive increments of the fibrous material, the material thus discharged being continuously replaced by fresh material fed into the forward end of the plug by the conveyor.

It is important to note that the perforations in the housing extend beyond the conveyor flight, to permit drainage of liquid from the highly compressed fiber, so that a dense plug may be formed, but terminate short of the end of the conveyor housing so that the rearward end of the fibrous plug may effectively block the housing to prevent leakage of pressure therefrom. Otherwise stated, the previous section of the housing is contiguous to the trailing portion of the screw, extends beyond the screw, and terminates short of the discharge end of the housing, as shown in the drawing.

The pressure applied by the screw to the fibrous plug is rather high, and it is desirable to distribute the force exerted by the plug against the end of the conveyor flight. This result is achieved by deflecting the flight end into a plane substantially perpendicular to the axis of the conveyor shaft, as shown more particularly in Figure 5 of the drawing. As is apparent from this figure, the trailing face 26 of the conveyor flight defines such a plane, so that the pressure is distributed over a considerable area at the end of the plane. The end face 26 of the flight, as well as the opposite, forwardly directed face 27 may be further strengthened by the addition of reinforcing metal, deposited by welding.

In order to promote the formation of a dense plug at the discharge end of the conveyor, and to prevent the plug from blowing out as the result of the pressure within the zone or system from which the fibrous material is removed, it is highly important to provide means whereby the conveyor outlet is restricted and pressure is exerted against the rear of the plug. Furthermore, it is important that the pressure so applied to the rear of the plug be so varied as to compensate both for momentary and for prolonged variation in the plug density, in the frictional resistance exerted at the plug periphery and along the shaft, and in the pressure tending to force the plug out of the conveyor. We prefer to employ for this purpose a conical member 30, mounted on and preferably rotating with the conveyor shaft 20, for instance by a splined connection between the member 30 and the shaft, whereby the member may be displaced axially of the shaft toward and away from the discharge end of the conveyor housing, the precise position of the member 30 on the shaft at any instant being determined largely or entirely by operating conditions. In order that the member 30 may be automatically displaced in an axial direction in response to momentary or rapid change in operating conditions, a coiled spring 34 is employed, this spring engaging the rear face of the conical member 30 at one end and the forward face of a sleeve 35 at its other end, sleeve 35 being keyed to shaft 20 for axial displace-

ment thereon and rotation therewith, and serving as an abutment for the spring 34. Thus if it be assumed that sleeve 35 occupies a fixed position axially of the shaft 20, it will be perceived that the spring 34 will yieldingly urge the cone member 30 against the fibrous plug, and will be compressed or expanded to compensate for irregularities in the density of the plug, in the frictional resistance to movement of the plug, or in the discharging pressure applied thereto, the regulating action being thereby quickly and automatically effected.

Since the action of the spring 34 in regulating the plug pressure is effective only as to relatively small but rapid changes in operating conditions, compensation for wider and more prolonged variation in the plug density or the discharging pressure is obtained by adjusting the sleeve or abutment 35 axially of the shaft, whereby the range of movement of the conical member 30 permitted by the spring 34 is correspondingly displaced. For this purpose we may employ mechanism such as is shown more particularly in Figure 3, whereby the position of sleeve 35 on the shaft may be altered during operation of the conveyor. Thus a sleeve 38 surrounding the shaft 20 and journaled for rotation in a boss 39 formed on a gear housing 40 engages the sleeve 35 through a thrust bearing 42, so that axial displacement of sleeve 38 in a forward direction, or toward the conveyor, effects corresponding displacement of abutment sleeve 35, spring 34, and conical member 30. Screw threads 44, formed on sleeve 38, are engaged by cooperating threads formed on a nut 45 suitably journaled in gear housing 40 for rotation about the axis of shaft 20. Formed on the periphery of nut 45 is a worm gear 46, the latter being driven by a worm 47 keyed to a shaft 48, the latter being journaled in gear housing 40 for rotation on an axis transverse to the axis of conveyor shaft 20. It is thus apparent that by rotating shaft 48, the cone member 30 may be displaced axially to a position in which the requisite pressure is applied against the fibrous plug, minor and rapid variations in the applied pressure being exerted by the spring 34 as hereinbefore described. The adjustment may be made manually, for example by a hand wheel on shaft 48, or automatically in response to variation in operating conditions as measured by the resistance offered to rotation of the conveyor shaft 20 by the fibrous mass.

During the passage of the fiber and entrained liquid through the outlet portion of the conveyor, liquid is expressed from the fiber through the perforations in the conveyor housing, whereby the ratio of liquid to fiber is materially decreased. Reduction of the liquid to fiber ratio of from 25 to 1 at the inlet end to 1:1 or even less at the discharge end may be readily effected by the apparatus described, and a plug may be formed which is of sufficient length and density to retain pressures in the system of from 50 to 175 pounds per square inch or even higher, provided the impervious portion of the housing immediately adjacent its discharge end is of sufficient length to enable the plug to block the housing, as hereinbefore pointed out, and provided the preceding pervious portion extends sufficiently beyond the conveyor flight to allow adequate expression of liquid from the plug.

In order that the plug discharged from the conveyor may be prevented from packing beyond the conveyor housing, and may be broken up for

further treatment, it is preferable to provide picker pins 50 for engagement with the plug as it emerges from the conveyor. These pins may be mounted in bosses 51 formed on the sleeve 35, so as to rotate with the conveyor shaft 20, whereby the fibrous plug is effectively disintegrated, knots and lumps are eliminated, and subsequent suspension of the fiber in liquid and its uniform impregnation by the liquid is facilitated. It should be noted that the axial adjustment of sleeve or abutment 35 as hereinbefore described, to vary the pressure applied to the plug by conical member 30, also serves to displace the picker pins axially. The position of the pins is thus determined independently of the action of spring 34, and the pins are not permitted to yield on variation in the pressure applied thereto, as is member 30, but are positively positioned and rotated. The dewatered stock falls downwardly through an outlet passage 54, either to the atmosphere or to a further treating zone of less pressure than that of the system from which the stock is withdrawn.

In order to insure against possible blowing out of the plug as the result of unusual pressure conditions, we prefer to discharge the stock from outlet passage 54 through a rotary valve housing 55, in which is supported for rotation a valve having a plurality of radially directed blades 56. The valve blades 56 may be driven through gearing from any suitable source of power which is so designed as to transmit only a predetermined maximum torque to the valve, sufficient to move the discharging stock through the housing 55, but insufficient to rotate the valve when the latter is subjected to the high pressure resulting from the blowing out of the fibrous plug. Thus if the plug should fail to hold the pressure, the rotary valve will jam and release of pressure in the zone or system from which the material is being withdrawn will be blocked. The valve thus contributes an important safety factor in the operation of the conveyor.

One method of driving the rotary valve is illustrated in Figure 1, the valve shaft being rotated through screw gearing 57 and belt gearing 58 from a motor 59. On the occurrence of a plug blow-out, the belt gearing 58 will slip and rotation of the valve will terminate. Various other expedients effective to interrupt the drive in response to excessive torque, such as a slip clutch, a frangible pin, or a torque responsive control for the motor circuit may be employed in lieu of the drive shown in the drawing.

It will be appreciated that the plug is broken off at its rearward end only to the extent that fresh material is pressed into its forward end. Thus the plug remains in position and continues to block the conveyor even though the supply of material to the conveyor be irregular or interrupted. Again, irregularity of supply does not interfere with expression of liquid from the fiber, any material supplied to the conveyor, however irregularly, being fed by the screw against and into the fibrous plug. This is the result of employing a continuous and uninterrupted conveyor that terminates short of the end of a uniformly dimensioned cylindrical housing in which it operates.

Under some circumstances we find it desirable to apply peripheral pressure to the discharging fibrous plug, and may employ for this purpose the structure illustrated in Figure 4. Thus one or more axially extending plates 60 may be pivoted to the annulus 24 for swinging movement

toward and away from the axis of the conveyor shaft 20, being yieldingly urged toward the shaft axis. A pressure pin 61, supported for displacement in the direction of its length toward and away from the shaft 20, and engaging the rear face of each plate 60, is yieldingly urged toward the plate by a coiled spring 63. Spring 63 engages at one end an abutment 64 on the shaft, and at its other end a plate 66, apertured to receive loosely therethrough pin 61 and threaded elements 68 secured to casing 15. By adjusting nuts 69 threaded on elements 68, plate 66 may be displaced to vary the compression of spring 63 and thereby to vary the range of swinging movement of plates 60. Thus, as in the previously described embodiment, the pressure applied to resist the movement of the plug out of the conveyor is automatically varied over small ranges by flexure of spring 63, whereas prolonged change in operating condition may be compensated by manipulating nuts 69 to displace the abutment for the spring. Preferably three pressure plates 60, distributed about the periphery of the conveyor, are employed to effect satisfactory distribution of the applied pressure; only one is shown in the drawing in the interest of simplicity and clarity.

Turning now to Figure 6, wherein is illustrated an embodiment of the invention adapted particularly for the introduction of fibrous material into a zone of substantial pressure from a zone of less pressure, it will be observed that the structure is generally similar to that shown in Figure 1, corresponding elements bearing the same reference characters. The principal difference resides in the conveyor housing 70, which is pervious to liquid over its entire forward portion, but impervious to liquid over its rearward portion, designated at 71. By providing perforations in the conveyor housing adjacent the forward portion, adequate drainage or expression of liquid from the fiber is assured, and by terminating the perforations at a point forward of the discharge end of the conveyor housing but rearward of the conveyor flight, release of pressure from the system into which the conveyor is charging is prevented by a dense fibrous plug, formed beyond the end of the conveyor flight, as explained more fully in connection with the embodiment of Figure 1.

It is frequently desirable to wash the fibers prior to their introduction into a further treatment zone, either for the purpose of removing or diluting liquid employed to impregnate the fibers in a preceding zone, or to effect preliminary impregnation of the fibers with a treatment liquid which is effective in a subsequent zone. This result may efficiently and conveniently be achieved in the modified form of the apparatus shown in Figure 2. In this embodiment the conveyor housing 13 is preferably perforated over the greater part of its length to facilitate the discharge of a large volume of liquid. The conveyor shaft 20 is hollow, liquid being introduced into the shaft at one end of the shaft, and being discharged into the fibrous material through perforations 75 formed in the shaft adjacent the end of the conveyor flight. When the fibrous material approaches the end of the conveyor flight, much of entrained liquid has drained therefrom, so that the liquid introduced through the shaft as described readily permeates the fibers. By reason of the high pressure developed in the plug section of the conveyor, just beyond the conveyor flight, a considerable amount of the

liquid so introduced is squeezed out and discharged through the openings in the conveyor housing. It is thereby possible, by introducing water through the conveyor shaft, to wash the fibrous stock effectively without materially decreasing the consistency of the same as discharged from the conveyor.

The present invention lends itself particularly well to the treatment and handling of cotton linters, it being found that a substantially uniform output of stock, having uniform consistency, can be obtained even though the volume and consistency of stock delivered to the apparatus may vary over substantial ranges. By the use of relatively small perforations in the conveyor housing, for example of the order of $\frac{1}{8}$ inch or less, loss of fiber is reduced to a minimum and may be further reduced by recirculating liquid expressed from the fibers, either through the same conveyor or through another of a series of conveyors, each constructed as hereinbefore described. Apparatus embodying the inventive principles set forth herein is relatively inexpensive to construct, maintain and operate, and is exceedingly durable as compared with equipment heretofore employed for similar purposes.

Having thus described the invention, what is claimed as new and desired to be secured by Letters Patent is:

1. In apparatus for use in processing cotton linters, the combination with a screw conveyor including a cylindrical housing having a liquid pervious wall and a screw having a working fit in said housing and terminating short of the discharge end thereof, said screw having a continuous helical flight of uniform pitch and diameter throughout the length thereof, and having a shaft of uniform diameter, means delivering to the inlet end of said housing a slurry of cotton linters and liquid, plug forming means adjacent the discharge end of said housing, said plug forming means comprising a member having a conical surface increasing in diameter in the direction of feed of the material, said member being supported for movement axially of said screw and having a maximum area in transverse section substantially less than the transverse sectional area of said housing, resilient means yieldably urging said member toward the discharging linters, an axially displaceable abutment for said resilient means, said abutment being mounted for rotation with said screw, mechanism for effecting axial displacement of said abutment to alter the working range of said resilient means, and picker pins rotatable with said screw and extending toward the discharging linters to effect disintegration of the linters plug.

2. In apparatus for use in processing cotton linters, the combination with a screw conveyor including a cylindrical housing having a liquid pervious wall and a screw having a working fit in said housing and terminating short of the discharge end of the housing, said screw having a continuous helical flight of uniform pitch and diameter throughout the length thereof, and having a shaft of uniform diameter, means delivering to the inlet end of said housing a slurry of cotton linters and liquid, plug forming means adjacent the discharge end of said housing, said plug forming means comprising a member having a conical surface increasing in diameter in the direction of feed of the material, said member being supported for movement toward and away from the discharging linters, resilient means yieldably urging said member toward the

discharging linters, and picker pins rotatable with said screw and extending toward the discharging linters to effect disintegration of the linters plug.

3. Apparatus as claimed in claim 2 in which the liquid pervious wall of the housing embraces a substantial length of the trailing portion of the screw, extends beyond the screw, and terminates short of the discharge end of the housing.
